MELVIN ROLSTAD, OF WORTHINGTON, MINNESOTA

SUCTION OPERATED HAIR CLIPPER

Application filed May 29, 1930. Serial No. 457,356.

This invention relates to improvements in cutting devices and pertains particularly to an improved form of hair clipper.

The primary object of the present invention 5 is to provide a hair clipper designed for operation by suction or vacuum.

As is, of course, well known the majority or hair clipping devices are operated by electricity, but it may not always be convenient 10 to obtain a supply of electric current in places where a clipper is to be used whereas it is nearly always possible to obtain a power means capable of actuating a suction pump and the clipper structure embodying the present invention is particularly designed for operation by a suction pump or by any means 15 which is capable of withdrawing or sucking air from an attached receptacle, as for example the device may be connected for use 20 to the intake of an internal combustion engine or similar machine where a constant suction exists while the machine is in operation.

Another object of the invention is to provide a novel means for coupling together a 25 movable cutter bar, a pair of pistons each operating in a cylinder which is intermittently exhausted, and a valve mechanism for alternately connecting the exhaust or suction pipe of the device with the cylinders, whereby a 30 smooth operation of the cutter is obtained free from any shaking or vibration.

The invention will be best understood from a consideration of the following detailed description taken in connection with the accompanying drawings, forming part of this specification, with the understanding, however, that the invention is not confined to any strict conformity with the showing of the drawings 35 but may be changed or modified so long as such changes or modifications mark no material departure from the salient features of the invention as expressed in the appended claims.

45 In the drawings:

Figure 1 is a view in top plan of the cutter embodying the present invention, minus the cover or casing therefor.

50 Figure 2 is a central longitudinal section taken on the line 2-2 of Figure 1.

Figure 3 is a transverse sectional view taken on the line 3-3 of Figure 1.

Figure 4 is a transverse sectional view taken on the line 4-4 of Figure 1.

Figure 5 is a horizontal sectional view 55 taken on the line 5-5 of Figure 2.

Figure 6 is a detailed sectional view of one of the pistons.

Figure 7 is a detailed sectional view of a control valve for the suction tube of the implement. 60

Figure 8 is a view partly in top plan and partly in section of a modified form of the suction mechanism which may be employed in connection with the present clipper. 65

Referring more particularly to the drawings wherein like numerals of reference indicate corresponding parts throughout the several views, the numeral 1 indicates generally the bottom of the cutter device embodying the present invention which bottom, as shown, comprises a relatively thick plate of oblong configuration. At one end, which is the forward end of the cutter, the plate is formed to extend upwardly at an obtuse angle as indicated at 2 and to this upturned portion or flange there is secured by means of the screws 3 the cutter head indicated generally by the numeral 4 and which comprises the under or fixed plate 5 along the forward edge of which the fixed teeth 6 are formed, and the shiftable plate 7 which is mounted upon the top face thereof and has the teeth 8 formed along the forward edge for reciprocation over the fixed underlying teeth 6. 70 This movable plate 7 is maintained in position upon the fixed plate 5 by the lugs 9 which extend through the elongated slots 10 formed in the movable plate. This construction is usual and forms no part of the present invention. The rear edge of the movable plate 7 is provided at a point intermediate its ends with the recess 11 in which engages the head portion 12 of the oscillating actuating bar which is indicated as a whole by the numeral 13. 75

The cutter operating bar 13 is mounted adjacent its forward end upon the post 14 which is positioned upon the top of the base 1 upon the longitudinal center thereof and 100

a screw 15 passes through the bar 13 and engages the post to maintain the bar in place thereon.

Directly behind the post 14 the bar 13 is formed to provide a depending finger 16 and is also arched slightly as indicated at 17, this arched portion terminating in a down turned rear end 18 and a fork 19 the arms of which carry adjacent their ends the inwardly directed opposed studs 20.

The base 1 is provided with a bore 21 which constitutes a suction tube and this bore is preferably formed to extend from the rear end of the plate longitudinally thereof in the manner shown, terminating at its forward end in the upwardly directed outlet 22 which opens through the top of the base plate. At each side of the aperture 22 which communicates with the suction tube 21 there is formed in the plate an aperture 23 each of which is in communication with a passage or tube 24 which leads to the far side of the base plate from the point where it opens out through the top thereof, as clearly shown in Figure 1, and terminates in an upwardly directed outlet 25 at a point rearwardly of the point where the outlets or apertures 22 and 23 are located. As shown in Figure 1 the apertures 22 and 23 are in alignment transversely of the base 1 and are disposed with the outlet 22 upon the longitudinal center thereof, while the outlets 25 are also in alignment transversely of the plate but are widely separated, one being at one side of the plate while the other is at the opposite side.

Disposed transversely of the base plate 1 with its longitudinal center in the same vertical plane as the plane in which the apertures 25 are disposed, is a split cylindrical shell 26 each edge of which is provided with a laterally extending lip 27.

These lips 27 are drawn together by a pair or more of screws 28 which pass therethrough and are in threaded engagement with the upper end of supporting posts 29 mounted upon the plate 1, thus drawing the lips 27 tightly down onto these posts. Opposite the lips of the shell 26 there is formed through the wall thereof and intermediate its ends an opening 30 through which the rear end portion 18 of the bar 13 extends, disposing the fork 19 within the shell and with the studs 20 thereof in vertical alignment and in the same vertical plane as the longitudinal center of the shell.

Within the shell 26 at each end thereof there is positioned a cylinder 31. Each of these cylinders is open at its inner end as shown in Figure 3 and as is also shown in this Figure these open ends of the cylinders are spaced apart a distance substantially equal to the width of the opening 30. It will, of course, be understood that the cylinders 31 are tightly gripped by the shell when the lips 27 thereof are drawn together in the

manner described so that they will be held against relative movement. Each end of the shell 26 and the cylinder therein is provided with an aperture 32 which communicates with the adjacent aperture 25 forming the rear terminal of a passage 24.

Mounted within each cylinder is a piston indicated generally by the numeral 33. Each of these pistons comprises an inner and outer plate 34 and 35 respectively which is threadably mounted upon one end of a double connecting rod 36, the central portion of which is formed to provide a surrounding recess 37 in which the studs 20 of the operating bar yoke 19 engage.

The plates 34 and 35 of each piston grip therebetween the base portion of a cup washer 38 and the plate 34 of each piston has positioned in the peripheral groove 39 formed therein an annular coil spring member 40 which maintains the flange portion of the cup washer expanded so as to maintain relatively tight frictional contact with the inner surface of the encasing cylinder.

Mounted upon the top of the plate 1 forwardly of the cylinders 31 is a block 41 which has formed vertically therethrough a central passage 42 and at each side thereof a passage 43. The passage 42 communicates with the aperture 22 while the passages 43 each communicates with a passage 23.

Mounted over the rear of the block 41 is an inverted substantially U-shaped frame 44. The top of the frame carries upon its underside a depending pivot stud 45 while there is mounted in the block directly beneath the stud 45 an upwardly directed pivot stud 46.

Disposed upon one side over the block 41 is a substantially U-shaped oscillatable frame 47 the end of each leg of which is arcuately recessed as indicated at 48 to receive a stud 45 or 46 as shown in Figure 2. The yoke portion of this oscillatable frame 47 has attached thereto one end of a coil spring 49 while the other end thereof is attached, as shown in Figure 2, to the finger 16 carried by the cutter operating bar 13.

At each side of the oscillatable frame 47 there is an upstanding pin 50 which carries a resilient sleeve 51 which acts as a bumper against which the frame 47 engages when it is oscillated.

It will be readily seen from an examination of Figure 5 that upon moving the finger 16 transversely of the block 41, as it moves in the operation of the instrument, the frame 47 will be swung about the pivots 45 and 46 and this swinging will be with a snapping movement so that the yoke portion of the frame will snap back and forth between the bumpers 51.

Pivotedly attached to the lower side of the swinging frame 47 is a valve button 52 which slides over the face of the block 41 and alternately connects the passages 43 with the cen-

tral passage 42, through the medium of the recess 53 formed in the under face thereof as shown in Figure 4.

Adjacent the yoke portion of the frame 47 the arch 17 of the bar 13 carries a laterally extending arm 54 which terminates in a downwardly and inwardly directed finger 55. These fingers alternately engage the oscillatable frame 47 when the instrument is in use and give an initial movement thereto which is completed by the spring 49.

In the rear portion of the bottom plate 1 there is mounted in a recess formed transversely of the air exhaust passage 21 a valve block 56 which, when moved in one direction, closes the passage 21 as shown in Figure 7. This block is held in place by a plate 57, through which is formed a slot 58. A pin carried by an operating button 59 projects through the slot 58 for engagement with the block 56 so that the operator of the instrument may conveniently shift the block to control the suction of air through the passage 21 and thus control the operation of the cutter.

In operation a suitable pipe 60 is connected between the rear end of the passage 21 of the instrument and a suitable suction element. By opening the valve 56 the air will be sucked from that cylinder 31 in which the piston 33 is positioned adjacent the open end thereof. The other piston will, of course, be adjacent the closed or head end of its cylinder. When the pistons are in this position the valve button 52 will be so placed that the passage 24 which is in communication with the first mentioned cylinder or, in other words, with the cylinder where the piston is adjacent the base or inner end thereof, will be in communication with the suction or exhaust passage 21. As the air is exhausted from the one cylinder the pistons will move over and air will be drawn into the other cylinder through the passage which is in communication therewith and which at its other end is open to the atmosphere. As soon as the pistons have moved over to the limit of their movement one of the fingers 55 carried by the bar 13 which, of course, has had its rear end swung over from one side of the opening 30 to the other, with the pistons, will engage the swinging frame 47 and give to it a slight initial movement in the direction which the pistons are moving. The finger 16 to which the spring 49 is connected will have swung the forward end of the spring over in the direction which the pistons move to a point beyond the pivotal center of the frame 47 so that the yoke end of the frame, after being started by the finger 55 will be caused by the spring to snap over and thus shift the valve button 52 to the position where it will establish communication between the exhaust passage 21 and the other passage 24. The pistons and all of the other

elements will then be shifted back to the first position by duplication of the movements of the various parts in the manner just described.

From this it will be readily seen that by the application of continued suction to the pipe 60 and the passage 21 the oscillation of the bar 13 upon its pivot 15 and the movement of the cutter bar 7 across the fixed bar 5 necessary to perform a hair cutting operation, will be accomplished. The rapidity of the movement of the cutter may be controlled either by controlling the operation of the suction apparatus which is attached to the instrument or, if the suction apparatus is operating at a high rate of speed, through the manipulation of the valve 56.

In Figure 8 there is shown a modified form of suction producing mechanism which may be used in place of the cylinders 31 and pistons 33, if found desirable. In this form of suction mechanism there is provided a casing 61 which is in the form of a segment, it having an arcuate front wall 62 and the convergent side walls 63 extending from the ends of the front wall and terminating in spaced relation to provide an opening 64. Mounted upon the base of the instrument and closing the opening 64 is an oscillatable post 65 which turns about the pivot 66. The edges of the opening 64 may abut snugly against the post 65 and may be provided with suitable packing 67 to prevent air being drawn into the casing at the sides of the post. The post 65 upon the inside of the casing has cast integral therewith a fan blade 68 while at the outer side and diametrically opposite the blade 68 there is attached to the post the arm 69 which corresponds to the bar 13 in the preferred form of the invention. This arm carries a head 70 which engages the shiftable cutter bar of the clipper.

In each of the two corners formed at the points of joinder between the arcuate wall 62 and the walls 63 there is an outlet opening 71 each of which is provided for connection with one of the passages 25 in the base of the instrument.

While in the foregoing descriptive matter the cutter has been referred to as a hair clipper it is, of course, to be understood that it may be used for shearing sheep and other animals. It will also be readily understood that the clipper may be conveniently operated by connecting it with the vacuum tube on an automobile and for this reason it may be employed in places where electrical clippers or clippers of other types could not be used.

Having thus described my invention, what I claim is:

1. In a device of the character described, including a body, a fixed member and a movable member on the fixed member, a cylinder disposed transversely of the body and closed at each end and having an opening in the

- wall thereof, a valve block mounted upon the body forwardly of said cylinder and having three upwardly opening passages arranged in a line transversely thereof, means for connecting the center one of said three passages with a suction means, each of the outer ones of said passages being connected with one end of said cylinder, a pair of pistons in said cylinder having a connecting rod therebetween, a frame disposed over said block, a yoke of substantially U shaped design having the free end of one leg pivotally connected to said frame and the free end of the other leg pivotally connected to the block, a valve member carried by said yoke and slideable on the block to alternately connect the last mentioned passage with the passage communicating with the suction means, a bar pivotally mounted intermediate its ends between said members and said cylinder and having one end connected through said cylinder opening with said connecting rod and its other end connected to said movable member, a depending finger carried by said bar, and a spring member connecting said finger with said yoke intermediate the connected ends thereof, said yoke having the legs thereof substantially parallel with the bar at the limit of movement of each piston.
2. In a device of the character described, including a body, a fixed member and a movable member on the fixed member, a cylinder disposed transversely of the body and closed at each end and having an opening in the wall thereof, a valve block mounted upon the body forwardly of said cylinder and having three upwardly opening passages arranged in a line transversely thereof, means for connecting the center one of said three passages with a suction means, each of the outer ones of said passages being connected with one end of said cylinder, a pair of pistons in said cylinder having a connecting rod therebetween, a frame disposed over said block, a yoke of substantially U shaped design having the free end of one leg pivotally connected to said frame and the free end of the other leg pivotally connected to the block, a valve member carried by said yoke and slideable on the block to alternately connect the last mentioned passage with the passage communicating with the suction means, a bar pivotally mounted intermediate its ends between said members and said cylinder and having one end connected through said cylinder opening with said connecting rod and its other end connected to said movable member, a depending finger carried by said bar, and laterally directed arms carried by said bar, each terminating in a depending portion, each of said depending portions being arranged to engage said yoke to start movement thereof during an oscillatory movement of the bar.
3. In a device of the character described,

a base, an arm pivotally mounted intermediate its ends for oscillation, an element connected with one end of said arms for actuation thereby, a cylinder disposed transversely of the other end of the arm and comprising a pair of cylindrical bodies each having one end opened and said bodies being disposed with their open ends in spaced opposed relation, a longitudinally split cylindrical sleeve having said cylindrical bodies disposed therein, said sleeve having a lateral flange formed integral therewith and longitudinally of each of the edges of the split portion thereof, elements connecting said flanges to contract the sleeve about said cylindrical bodies, said sleeve having an aperture therein at a point between the opposed ends of the bodies to facilitate the extension of the other end of said arm into the cylinder, a piston in each of said cylindrical bodies, said pistons having a rigid connecting rod therebetween with which the said other end of the arm is connected, and valve controlled means for alternately drawing air from the cylindrical bodies from a point between the closed ends of the same and the pistons therein.

In testimony whereof I hereunto affix my signature.

MELVIN ROLSTAD.
